UNITED STATES PATENT OFFICE

2,040,708

ROAD GRADER LEVEL

Linus Persson, Braddock, N. Dak.

Application May 16, 1935, Serial No. 21,853

1 Claim. (Cl. 33—209)

My invention relates generally to a level to be mounted on a roadgrader to continuously and instantly inform the operator of the roadgrader of the actual crown on the road, and an important object of my invention is to provide a simple and structurally efficient arrangement of the character indicated which is accurate and dependable and easily installed.

Other important objects of my invention will be apparent from a reading of the following description in connection with the drawings, wherein for purposes of illustration I have shown a preferred embodiment of my invention.

In the drawings:—

15 Figure 1 is a transverse vertical sectional view taken through a roadgrader and showing the arrangement of the invention mounted on the drawbar of the roadgrader.

20 Figure 2 is a transverse vertical sectional view taken through one end of the arrangement showing the construction of one of the hydraulic indicators.

25 Figure 3 is an elevational view taken from the right of Figure 2.

Figure 4 is a horizontal sectional view taken through Figure 2 approximately on the line 4—4.

Figure 5 is a transverse vertical sectional view taken through Figure 1 approximately on the line 5—5.

30 Referring in detail to the drawings, the numerals 5 and 6 refer to the arched longitudinal members of the frame of the roadgrader which lie on opposite sides of and are mounted in connection with the drawbar which includes the side members 7 and 8. To the underside of the members 7 and 8 is mounted the framework 9 from which depend the arms 10 and 11 to the lower ends of which are connected the brackets 12 and 13 which are connected to the rear side of the roadbed engaging element 14.

35 In accordance with the present invention I mount on and across the upper edges of the grader frame members 7 and 8 the U-shaped frame which is generally designated 15 and which is of angle iron cross section with the vertical flange arranged forwardly and the remaining flange horizontally in protecting relation to the correspondingly shaped level gauge element which is generally designated 16 or I mount the U-shaped frame on the members 5 and 6.

40 The level gauge element 16 is composed of the relatively small pipe 17 which lies on the horizontal part of the frame 15 and connects by a reducing elbow 18 to the lower end of the larger tube 19 which is located behind the forward

flange of the corresponding vertical end of the frame 15 and laterally inwardly of the remaining flange thereof. The upper end of the tube 19 is closed by a plug 20 in which is screwed a bushing 21 through which works the piston rod 22 on the lower end of which is a float piston 23. Below the bushing 21 the rod 22 has squared teeth 24 on its laterally inward side which operatively engage pins 25 extending between and connected to spaced disks 26 and 27 which extend through an opening 28 in the laterally inward side of the upper part of the tube 19 and are rotatably mounted by and on an axle 29 journaled in lug portions 30 and 31, constituted by enlargements of the tube 19. The gauge is 15 mounted transversely on the frame bars 7—8 and intersects the diagonal scraper 14 at approximately its mid point.

5 The rear end of the axle 29 has fixed thereto the indicator hand 32 which cooperates with an 10 indicia equipped disk 33 which is mounted to the lug 31.

15 A roller 34 journaled on a shaft 35 extending diametrically across the tube 19 rolls against the laterally outward smooth side of the rod 22 in a 20 manner to preserve the alignment and easy working characteristics of the rod 22 and to hold the teeth 24 against the pins 25. It is obvious that this arrangement brings the rod 22 in between the disks 26 and 27, so that mutual cooperation exists between the roller 34, the rod 22, the inner sides of the disks 26 and 27, and the pins 25, whereby smooth and non-wearing action of the parts is assured.

25 The small pipe 17 is provided adjacent its opposite ends with control valves 36 and 37, respectively, while the center of the small pipe 17 has a riser 38 thereon provided at its upper end with a filling cap 38' enabling introduction of the leveling fluid which operates the floats 23.

30 U-bolts 39 and 40 encircle the ends of the small pipe 17 and traverse the horizontal flange of the frame 15 for holding the small pipe in place on the frame. An additional similarly arranged U-bolt 41 is centrally connected between the frame 45 and the small pipe, while U-shaped bolt clamps 42 and 43 encircle the tubes 19 for locking the same in place in the vertical end portions of the frame 15. The floats 23 will be of any suitable buoyant arrangement or construction and work 50 closely although sufficiently loose within the tubes 19.

35 It can be seen, that in the event the apparatus tilts downwardly toward the left in Figure 1, the fluid in the conduit 17 will rise in the tube 19, 55

lifting the float 23, which carrying the rack 24 therewith will rotate the wheel 26 located on the shaft 30 with the pointer 32. The variance in grade will be indicated by comparing the pointer 5 32 with the dial 33.

Although I have shown and described herein a preferred embodiment of my invention, it is to be definitely understood that I do not desire to limit the application of the invention thereto, and any 10 change or changes may be made in the materials and in the structure and arrangement of the parts, within the spirit of the invention and the scope of the subjoined claim.

What is claimed is:—

15 A level indicator comprising an elongated substantially horizontally disposed conduit, a fluid in

the conduit, upstanding tubular extensions at the ends of the conduit, a float in each of the extensions, a rack bar extending upwardly from each of the floats, a guide in one end of each of the extensions for slidably receiving the rack bar, one 5 side portion of each of the extensions being provided with an opening, a gear mounted in each opening for mesh with the adjacent rack, each of the said gears being provided with an external shaft, a gauge plate stationarily secured to the 10 outside of each of the extensions and through which the corresponding shaft extends, graduations on the gauge plate and a pointer secured to the corresponding shaft at the front of the said gauge plate.

15 LINUS PERSSON.
